CLAIM

The ornamental design for a golf divot tool, as shown and described.

DESCRIPTION

FIG. 1 is a front, right and top perspective view of a golf divot tool, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is another front, right and top perspective view of the golf divot tool in an alternate closed configuration.

1 Claim, 8 Drawing Sheets
